(57) **CLAIM**

The ornamental design for a wireless-earbud charging case, as shown and described.

DESCRIPTION

FIG. 1 depicts the top-left-front perspective view of the wireless-earbud charging case with the case lids closed.

FIG. 2 depicts the top-left-front perspective view of the wireless-earbud charging case with the case lids opened.

FIG. 3 depicts the bottom-left-front perspective view of the wireless-earbud charging case with the case lids opened.

FIG. 4 depicts the front view of the wireless-earbud charging case with the case lids closed.

FIG. 5 depicts the rear view of the wireless-earbud charging case with the case lids closed.

FIG. 6 depicts the left-side view of the wireless-earbud charging case with the case lids closed.

FIG. 7 depicts the right-side view of the wireless-earbud charging case with the case lids closed.

FIG. 8 depicts the top view of the wireless-earbud charging case with the case lids closed; and,

FIG. 9 depicts the bottom view of the wireless-earbud charging case with the case lids closed.

The broken lines in the Drawings depict portions of the wireless-earbud charging case that form no part of the claimed design.

1 Claim, 4 Drawing Sheets
